RAILROAD TRACK STRUCTURE

Filed Nov. 17, 1927

UNITED STATES PATENT OFFICE.

WILLIAM ORD, DECEASED, LATE OF CHICAGO, ILLINOIS, BY HARRIET PETTIBONE
ORD, EXECUTRIX, OF CHICAGO, ILLINOIS.

RAILROAD-TRACK STRUCTURE.

Application filed November 17, 1927. Serial No. 233,770.

This invention relates to improvements in railroad track structures and it consists of the matters hereinafter described and more particularly pointed out in the appended 5 claim.

The primary object of the invention is to provide an improved track for industrial and similar narrow gage railways, which may be easily laid without the necessity of the usual supporting cross ties, which needs no particular surfacing or other preparation of road bed preliminary to the laying of the track and which is stronger yet lighter in weight than the track structure heretofore 15 employed for the same purpose.

A further object of the invention is to provide a track of the kind which will greatly reduce the cost of making and maintaining a road bed therefor because it includes 20 rails of a peculiar character which form their own seats in rough and uneven ground and act to so engage and compact that portion thereof directly under the rails as to prevent lateral shifting of the rails under 25 traffic conditions.

These objects of the invention as well as the many advantages thereof, will more fully appear as the specification is proceeded with.

30 In the drawings:

Fig. 1 is a top plan view of a track for industrial and similar narrow gage railroads embodying the invention.

Fig. 2 is a transverse vertical section 35 through the same on an enlarger scale as taken on the line 2-2 of Fig. 1.

Fig. 3 is a view in side elevation of a fragment of the improved railroad track.

Fig. 4 is a transverse vertical section 40 on a further enlarged scale through one of the rails embodied in the improved track.

Referring now in detail to that embodiment of the invention illustrated in the accompanying drawings. The improved track 45 includes two parallel spaced rails, each made up of rail sections 1-1, with the ends of abutting rail sections of each rail connected or secured together by the usual fish plates or splice bar sections 2, the rail sections in one rail being so disposed as to bring the joints in one rail opposite the mid-portion of the sections in the other rail so that the joints of the rails in track are staggered. The rails are suitably connected together at

spaced intervals by tie bars 3 the construction of which will more fully appear later. 55

As the construction of the rail sections in each rail is the same, a detail description of one will suffice for both. Each rail section includes an upright web 5 with a head 6 at the top end thereof and a base 7 at the bottom end thereof. The major portion of bottom surface 8 of the base is substantially flat and horizontal while the top surface of said base is inclined downwardly and 60 outwardly from the web whose portions 9^a of said top surface adjacent the web being inclined in planes, corresponding to the under sides 6^a of the rail heads, while those portions 9 extending outwardly therefrom 65 are inclined at lesser angles. The marginal portions of the base are bent downwardly upon generous corners or curves to form substantially upright side flanges 10-10 respectively. In the manufacture of said rail 70 sections, said marginal portions extend horizontally as shown by the dotted lines 10^a in Fig. 4, the last pass through the rolls turning the said marginal portions downwardly 75 to provide said flanges. 80

As before stated, the rail sections of opposite rails are connected together by the tie bars 3. Each tie bar includes a bolt body 11 which extends through suitable holes 12 in the web 5 of the rail sections, and through 85 suitable holes in washer like members 13 on each side of said web, the outer ends of the bolts being threaded to receive the nuts 14-14. The washer like members 13, are preferably made from short pieces of standard splice bar sections, so that the bevelled top and bottom surfaces thereof may be drawn into snug fitting engagement with the under side of the rail head and the top surface portions 9^a of the rail base. To space 90 the rails and to maintain them in parallelism in the proper gage, I provide a spacing sleeve or tube 15 which surrounds the major portions of the bolts and engages at its ends with the inner washer like members 13-13 95 as best shown in Fig. 2. 100

In laying the improved track, the base portion of each rail section is engaged upon the ground chosen therefor with flanges 10 resting upon the surface thereof. The sections of opposite rails are then connected together by the tie bars 3 as before described and the sections in each rail are 105

connected by the splice bars 2. In use, when an industrial or like train is run over the track thus made, the flanges 10 enter the ground and due to the weight upon the rails, a downward pressure as indicated by the arrows 16—16 in Fig. 4 is imposed thereon. Such a pressure will also be imposed upon the ground directly beneath the base which will tend to push the same downward and outward as indicated by the arrows 17 in Fig. 4. The outward movement of the ground beneath the rail base is checked or resisted by the side flanges 10—10 and the downward movement thereof is resisted by the ground portion below the level of the bottom edges of the flanges which in fact presents a counter force in the direction of the arrows 18 in Fig. 4 with the result that a compaction takes place in that ground portion immediately below the base, which provides an ample support for the rails and load imposed thereon. When laid upon uneven ground the rails make their own seats and any tendency toward a lateral shifting or movement of the rails is resisted by the action of the side flanges.

It is apparent that with the rails of the improved track positioned as described, directly upon the ground, the rails receive more support than in ordinary narrow gage track employing cross ties. Therefore, it is capable of bearing more traffic without "sinking" and may be made lighter in weight at a greatly reduced cost. A track

made as described greatly reduces the cost 35 of making a road bed therefor and maintaining the same and at the same time may be easily laid and removed and transported from place to place of use.

While in describing the invention, many 40 details of embodiment of mechanical construction as well as form and arrangement of the parts therefor have been referred to, the same is to be taken as by way of illustration only except as may be pointed out 45 in the appended claim.

The invention claimed:

A narrow gage railway track embodying 50 therein parallel rails adapted to be laid directly upon the ground, each rail having a web, a head at the upper end of the web and a base at the lower end, the base having a flat underneath surface with lateral margins turned downwardly on relatively wide arcs 55 to form ground engaging flanges one at either side of the rail base, tie bolts extending through the webs of both rails, washer-like members on said bolts engaged with the inner and outer surfaces of the rails, nuts on the ends of said bolts and spacing sleeves 60 surrounding said bolts and engaging at their ends with the washer-like members on the inner surfaces of said rails.

In testimony whereof, I have hereunto set my hand, this 14th day of November, 1927.

HARRIET PETTIBONE ORD,
*Executrix of the Estate of William Ord,
Deceased.*
